[57] CLAIM

The ornamental design for a chemical container, substantially as shown and described.

DESCRIPTION

FIG. 1 is a perspective view of a chemical container showing our new design;

FIG. 2 is a top plan view;

FIG. 3 is a side elevational view, the opposite side being a mirror image thereof;

FIG. 4 is an elevational view looking from the left of FIG. 3;

FIG. 5 is an elevational view looking from the right of FIG. 3; and

FIG. 6 is a bottom plan view thereof.

*FIG. 1**FIG. 2**FIG. 3*

FIG. 4

FIG. 5

FIG. 6
